UNITED STATES PATENT OFFICE.

ALBERT G. REDMOND, OF FLINT, MICHIGAN, ASSIGNOR TO JACOB RICHARD FRANCIS,
OF FLINT, MICHIGAN.

MEANS FOR SUPPLYING FUEL TO INTERNAL-COMBUSTION ENGINES.

Application filed February 14, 1928. Serial No. 618,991.

This invention relates to certain new and useful improvements in means for supplying fuel to an internal combustion engine and is a continuation of my application for supplying fuel to charge forming devices, filed August 18, 1922, Serial No. 582,574, the object being to provide in addition to the means for supplying fuel to charge forming devices, means for supplying fuel to the cylinders of the engine above the throttle of the charge forming device so that the internal combustion engine can be readily started by delivering to the cylinders of the engine gasoline so as to prime the engine.

Another object of my invention is to provide in connection with the fuel supplying means priming means under the control of the operator whereby in normal operation of the fuel supplying means with the charge forming device, the priming means is inoperative.

A still further object of the invention is to provide means for heating the raw fuel in its passage to the cylinder of the engine above the throttle under the control of the operator so that the gas will be heated before being delivered to the internal combustion engine to enable the same to vaporize readily so that a priming charge will be delivered to the cylinders of the engine in such a condition that the engine can be readily started. I have found in practice with a fuel supplying means constructed in accordance with my invention as shown in the above referred to application, that the fuel in the fuel line from the main supply tank to the charge forming device is maintained under sufficient pressure to force the fuel directly into the cylinders of the engine and to accomplish this result I have provided a branch pipe leading from the fuel line to the intake manifold at the point of connection with the internal combustion engine and arranged within this branch line a valve on the dash of the motor vehicle to which the device is attached so that by opening the valve, the fuel will be injected directly into the internal combustion engine so as to prime the same for starting.

Other and further objects and advantages of the invention will be hereinafter set forth and the novel features thereof defined by the appended claims.

In the drawing I have shown diagrammatically the construction of my improved fuel

feeding means for internal combustion engines in which 1 indicates the internal combustion engine, 2 the intake manifold, 3 the charge forming device and 4 the main fuel tank which is located in a plane beneath the charge forming device.

Mounted within the tank 4 is an electrical pump 5 for supplying fuel directly to the charge forming device 3 through a pipe 6 which is provided with a branch pipe 7 connected to a valve casing 8 which is preferably mounted on the dash 9 of the motor vehicle to which the device is attached. Extending from the valve casing 8 is a pipe 10 herein shown provided with nipples 11 extending into the branches of the main intake manifold 2 so that fuel will be injected into the manifold at the point of connection and while I have shown the fuel supply pipe with nipples, it is of course, understood that these nipples can be connected directly with the cylinders of the engine or a single nipple employed entering the manifold at any desired point so as to inject raw gasoline into the induction pipe above the throttle of the charge forming device. Mounted within the valve casing 8 is a needle valve 12 controlling the passage of gasoline therethrough.

The electrical pump 5 is in electrical circuit with a battery 13, said circuit having a maker and breaker 14 driven and timed by the internal combustion engine so as to make and break the circuit for energizing and deenergizing the electro-magnet or solenoid of the pump for intermittently reciprocating the piston and the construction of the pump is substantially the same as shown in my application filed August 18, 1922, Serial Number 582,574, wherein when the circuit is completed, the piston of the pump is raised and when the circuit is broken, the piston is allowed to drop for forcing gasoline out of the pump cylinder through the pipe line 6 directly into the fuel bowl of the charge forming device, which is provided with the usual float valve for operating a needle valve for controlling the needle which is held on its seat under substantially two pounds pressure, whereby the fuel in the fuel line pipe 6 will be maintained under substantially two pounds pressure at all times.

By the particular construction of pump and manner of connecting the same to the charge forming device as clearly described in the

above referred to application, the stroke of the piston of the pump is determined by the consumption of fuel in the charge forming device so that the fuel is maintained in the 5 fuel line pipe extending from the main supply tank to the charge forming device under pressure at all times whereby when the level of the fuel drops in the charge forming device, fuel is instantaneously delivered into the 10 bowl of the charge forming device. The maker and breaker or timing device for completing the circuit is preferably driven by the internal combustion engine so that the circuit is made and broken, as for example, every 15 twenty revolutions of the internal combustion engine so that the piston of the pump is raised and allowed to drop to supply fuel constantly to the charge forming device, but of course, the number of times that the circuit is made 20 and broken is determined by the engine to which the device is applied.

The electrical pump 5 is also in electrical circuit through a push button 16 arranged on the dash 9 to be manually operated for energizing the solenoid so as to raise the piston of the pump by allowing the electrical energy to flow through the solenoid which provides means for manually operating the pump independent of the engine operating means 30 whereby the pump can be operated so as to supply an additional amount of fuel when desired and it is especially adapted to be used in case of leakage or in starting a new motor vehicle. This push button also enables the injecting of a continuous supply of fuel into the internal combustion engine above the throttle when the valve 12 is opened by intermittently pushing the button 16. Arranged over the 35 branch pipe 7 is a heating element in circuit with the battery through a push button 18 whereby the fuel in the branch pipe will be heated before being delivered to the internal combustion engine for priming purposes.

While I have only shown diagrammatically 45 the means for supplying fuel to a charge forming device timed by the internal combustion engine, the construction is substantially the same as shown in my application Serial No. 582,574, wherein fuel is pumped from a main 50 fuel tank to the charge forming device by an electrical pump so constructed that the fuel in the pipe line extending from said charge forming device to said pump is maintained under sufficient pressure to lift the fuel to such 55 a height that it can be injected directly into the cylinders of the engine around the charge forming devices for priming purposes and I have shown means for accomplishing this result in the form of a branch line extending 60 from the main fuel line pipe to the engine, said branch line being provided with a manually operated valve upon the opening of which pressure in the fuel line will inject fuel to the cylinders of the internal combustion engine. 65

From the foregoing description it will be seen that I have provided in combination with means for supplying fuel to a charge forming device in the form of an electrical pump so constructed to supply fuel from a low level 70 tank to the charge forming device to maintain in the pipe line extending from said tank to said charge forming device, fuel under pressure in connection with a branch from said fuel line pipe to a point above the charge 75 forming device under the control of the operator whereby an additional charge of fuel can be injected into the manifold or directly into the cylinders of the engine and while I am aware that electrical primers have been 80 produced, my invention consists in the combination of a priming device and means for supplying fuel to the charge forming device.

What I claim is:—

1. Means for supplying fuel to internal 85 combustion engines comprising an electrical pump for elevating fuel from a main supply tank directly to the charge forming device of said engine so as to maintain fuel under pressure in the pipe line connecting said 90 charge forming device to said pump, and a branch line extending from said pipe line to the intake manifold, said branch line having a manually operated valve controlling the supply of fuel therethrough. 95

2. The combination with an internal combustion engine having an intake manifold, charge forming device and throttle valve for controlling the passage of explosive mixture to said engine, of a main supply tank arranged in a plane below said charge forming device, means for forcing fuel out of said supply tank to said charge forming device and maintaining the same under pressure, said means being controlled by the internal combustion engine, manually operated means for operating said means and a branch line extending around said charge forming device in communication with the intake manifold above the throttle for supplying additional fuel to said internal combustion engine. 100 105 110

3. Means for supplying fuel to an internal combustion engine comprising a pump for elevating the fuel from the main supply 115 tank directly to the charge forming device of said engine so as to maintain the fuel under pressure in the pipe line connecting said charge forming device to said pump, a branch line extending from said pipe line in communication with the engine, means for heating the fuel passing through said branch line and a valve arranged within said branch line for controlling the passage of fuel therethrough. 120 125

4. The combination with an internal combustion engine and charge forming device therefor, of means for lifting the fuel from a main supply tank to the charge forming device thereof and maintaining said fuel un- 130

- der pressure and means for by-passing a portion of said fuel above said charge forming device for priming the engine.
5. The combination with an internal combustion engine having an intake manifold, charge forming device and a main supply tank located in a plane beneath said charge forming device and connected thereto by a supply pipe, of means for forcing fuel through said supply pipe and maintaining said fuel in said pipe under pressure and a branch pipe extending from said supply pipe to the intake manifold and a valve in said branch pipe for controlling the passage of fuel therethrough.
10. The combination with an internal combustion engine having an intake manifold, charge forming device and a pipe leading from said charge forming device to a main supply tank located in a plane below said charge forming device, of means for forcing fuel through said pipe to said charge forming device and maintaining the fuel therein under pressure, a branch pipe by-passing said charge forming device in communication with the intake manifold of said engine and a valve in said branch pipe for controlling the passage of fuel therethrough whereby fuel can be injected directly into said manifold above the charge forming device by opening said valve for priming said engine.
15. In an internal combustion engine, the combination with a charge forming device for supplying explosive mixture thereto, of a supply tank arranged in a plane beneath said charge forming device, a pump for elevating fuel from said supply tank to said charge forming device and maintaining said fuel in the pipe line connecting said charge forming device to said tank under pressure and a valve controlled by-pass extending from said pipe line in communication with said engine whereby fuel can be injected by the pressure within the fuel line pipe directly to the cylinders of the engine.
20. The combination with an internal combustion engine, a charge forming device and a fuel supply tank for supplying fuel thereto, of a pump for forcing fuel from said tank to said charge forming device and maintaining said fuel under pressure and an electromagnet for operating said pump, means governed by the internal combustion engine for intermittently energizing said electromagnet, manually operated means for energizing said magnet and means under the control of the operator for by-passing a portion of said fuel around said carburetor and injecting the same directly to the internal combustion engine for priming said engine.
25. The combination with an internal combustion engine having an intake manifold, charge forming device, main fuel supply tank and a pipe leading from said tank to said charge forming device, of an electrically operated pump for forcing fuel through said pipe and maintaining fuel therein under pressure, manually operated means for operating said pump, a branch pipe extending from said pipe to the intake manifold, means for heating the fuel passing therethrough and a valve arranged in said branch pipe for controlling the passage of fuel therethrough.
30. The combination with an internal combustion engine having an intake manifold, charge forming device, main fuel supply tank and a pipe leading from said tank to said charge forming device, of an electrically operated pump for forcing fuel through said pipe and maintaining fuel therein under pressure, manually operated means for operating said pump, a branch pipe extending from said pipe to the intake manifold, means for heating the fuel passing therethrough and a valve arranged in said branch pipe for controlling the passage of fuel therethrough.
35. The combination with an internal combustion engine having an intake manifold, charge forming device and a supply pipe for said charge forming device extending from a tank located in a plane below said charge forming device, of means for forcing the fuel from said tank to said charge forming device through said pipe and maintaining the fuel therein under pressure and manually operated means for by-passing a portion of said fuel around said charge forming device for injecting said fuel into said manifold above said charge forming device.
40. The combination with an internal combustion engine having a charge forming device, a fuel supply tank located in a plane below said charge forming device, a pipe connecting said supply tank to said charge forming device, means for forcing fuel through said pipe and maintaining said fuel under pressure and means for utilizing the pressure of said fuel for by-passing a portion of said fuel around said charge forming device to the internal combustion engine.
45. Means for supplying fuel to internal combustion engines comprising means for elevating fuel from the main supply tank directly to the charge forming device, and maintaining the same under even pressure in the pipe line, and a branch pipe extending from the pipe line to the intake manifold, and a valve in said pipe line for controlling the supply of fuel therethrough, whereby a priming charge can be injected into the manifold under pressure.
50. In testimony whereof I hereunto affix my signature.

ALBERT G. REDMOND.
